UNITED STATES PATENT OFFICE.

GEORGE BITTLE, OF SHARONVILLE, OHIO.

SIGN.

No. 874,156.

Specification of Letters Patent.

Patented Dec. 17, 1907.

Application filed January 2, 1907. Serial No. 350,544. (Model.)

To all whom it may concern:

Be it known that I, GEORGE BITTLE, a citizen of the United States, residing at Sharonville, in the county of Hamilton and 5 State of Ohio, have invented certain new and useful Improvements in Signs, of which the following is a specification.

My invention relates to imitation glass signs for wagons and the like.

10 I have filed a sample of the sign herewith.

The object of the invention is to attach metal foil letters, characters or devices, to the rear face of a strip of transparent sheet celluloid.

15 My invention is shown in accompanying drawing, forming a part of this specification in which,

Figure 1 represents a face view of a celluloid sheet with the lettering applied. Fig. 20 2 is a cross section of Fig. 1.

To accomplish this I pounce an impression of the character on the front face of the celluloid sheet 1, I apply a sizing on the rear face of the sheet 1 consisting of a solution of 25 alcohol, ammonia and gelatin, which solution I find adheres in a thin coating to the oily surface of the celluloid sheet 1. I apply the gold or silver leaf 2 to this sizing, varnish the letter or character on the rear of the 30 foil, wet and rub away the unvarnished part of the foil, and then apply a back-ground of suitably colored paint over the back of the letter or character and sheet. The gelatin

burnishes the display surface of the character and imparts to it a fine luster. The 35 character or device is displayed from a front view of the celluloid sheet 1 with remarkable beauty and luster. The celluloid sheet 1 can be readily applied and removed, it is flexible and non-breakable, and at the same 40 time presents the beautiful finish of gilt lettering on glass.

Preferably the letter is formed of gold or silver leaf 2, marginally arranged, leaving an intermediate unburnished portion 3 of a 45 different color. The effect of this is very beautiful and causes the letter to stand out with marked clearness.

Having described my invention, I claim:—

1. A sign consisting of a sheet of transparent celluloid with a character formed of metal foil adhesively secured to the rear face thereof, and a background formed behind the character and sheet, substantially as described.

2. A flexible transparent sheet, having a metal leaf character on the rear face, and a display back-ground in rear of the sheet and character, substantially as described.

55 20 25 30 35 40 45 50 55 60 In testimony whereof, I have hereunto set my hand.

GEORGE BITTLE.
